No. 791,169.

PATENTED MAY 30, 1905.

M. SUBBER.

SPINDLE.

APPLICATION FILED OCT. 17, 1904.

UNITED STATES PATENT OFFICE.

MORRIS SUBBER, OF WOODBINE, NEW JERSEY.

SPINDLE.

SPECIFICATION forming part of Letters Patent No. 791,169, dated May 30, 1905.

Application filed October 17, 1904. Serial No. 228,668.

To all whom it may concern:

Be it known that I, MORRIS SUBBER, a citizen of the United States, residing at Woodbine, in the county of Cape May and State of New Jersey, have invented certain new and useful Improvements in Spindles, of which the following is a specification.

My invention has relation to a spindle of the class or type wherein the spindle proper is fixed and is surrounded by the rotating whirl upon which the bobbin is secured; and in such connection it relates more particularly to the construction and arrangement of parts constituting such a spindle.

15 The principal objects of my invention are, first, to provide a spindle wherein the whirl and its extension are properly centered and supported upon the fixed part of the spindle and the same provided with ball-bearings both 20 at the top and bottom thereof, each ball-bearing being adjustable independently of the other; second, to provide, in connection with such a whirl and its extension, springs or tension-fingers carried by the whirl extension at 25 or near its top and designed to clamp the bobbin to the whirl and its extension and to prevent lateral or vertical movement of the bobbin on the whirl and its extension, and, third, to provide, in such a spindle, means for lubricating both the upper and lower bearings 30 therefor while in operation.

The nature and scope of my present invention will be more fully understood from the following description, taken in connection with the accompanying drawings, forming part 35 hereof, in which—

Figure 1 is a vertical sectional view of a spindle embodying main features of my invention and of the bobbin supported on the 40 whirl and the extension of the same of the spindle. Fig. 2 is an enlarged side elevational view of the spindle with the bobbin removed. Fig. 3 is a cross-sectional view on the line 3-3 of Fig. 2, and Fig. 4 is a sectional detail view 45 of the upper end of the whirl extension, showing also the cap-piece with its ferrule.

Referring to the drawings, *a* represents the fixed spindle, which has near its base a bearing-block *a'*, having an annular groove to receive the balls *a²* of a ball-bearing. Surround-

ing this block *a'* is a whirl *b'*, which in its interior is screw-threaded to be removable from the screw-threaded exterior of said block *a'*, and thus to form with the balls *a²* and block *a'* a ball-bearing for the whirl *b'*. The whirl *b'* is provided with an upwardly-projecting tube or extension *b*, which surrounds the upper free end of the fixed spindle *a* and is arranged to revolve with the whirl *b'* around the same. The top of the spindle *a* is provided with a V-shaped depression *a⁶* to receive a ball *a³*, and the tube *b* of the whirl *b'* extends above the grooved top of the spindle *a* in the form of a removable cap-block *b³*, provided with a V-shaped depression to form, with the ball *a³* and top of the spindle *a*, an upper ball-bearing *b⁵*, designed to center and to hold the whirl in a central position upon the top of the spindle *a*. Fitting in the whirl-tube *b* and in a cap-block *b³*, closing the upper end of the whirl-tube *b*, are springs *d*, the ends of which are mounted, respectively, in said whirl-tube and in a sleeve *b⁵*, and the body of these springs is bellied out to form a resilient bearing, over which the bobbin *e* is slipped. These springs *d* form a rigid connection for the upper end of the bobbin on the whirl-tube *b* and prevent lateral as well as vertical movement of the bobbin on said whirl and its tube. The sleeve *b⁵*, which loosely surrounds the upper end of the whirl-tube *b*, is provided with grooves *b⁶*, in which the upper ends of the springs *d* are placed and in which the same are afforded a certain range of movement caused by the pressing inward of the springs *d* by the bobbin *e*. The cap-block *b³* is arranged to be advanced or retracted in an interior screw-threaded portion in the free end of the whirl-tube *b*, and a ferrule *f* is arranged to engage the cap-block *b³* and to bear down upon the end of the whirl-tube *b* and the sleeve *b⁵*. The cap-piece *b³* may be advanced or retracted in both the ferrule *f* and the whirl-tube *b* and when in proper position within the whirl-tube is locked by the ferrule *f* in said position. The cap-block *b³* has a vertical duct *b⁴*, through which oil may be introduced from the open top end of the ferrule *f* to lubricate the upper ball-bearing and the space between the whirl-tube *b* and the fixed spindle *a*. The

lower portion of the spindle a has a vertical duct a^4 and a transverse duct a^5 , leading therefrom to the ball-bearing of the whirl b' . Oil is forced from a cup or reservoir g through 5 these ducts a^4 and a^5 to the ball-bearing and the space between the spindle a and the whirl b' by advancing the cup or reservoir g upward on the spindle a . To so advance the reservoir, its exterior is screw-threaded and 10 fits into the screw-threaded interior of a bracket g' , fixed on the spindle a , as clearly illustrated in Fig. 1. Instead of forming the whirl b' and whirl-tube b separate the whirl b' may be provided with an integral tubular 15 extension b .

Having thus described the nature and objects of my invention, what I claim as new, and desire to secure by Letters Patent, is—

1. In a device of the character described, a 20 fixed spindle, a whirl-tube surrounding the same, removable means closing the free end of the tube, a whirl carrying the whirl-tube, an adjustable ball-bearing interposed between the whirl and the spindle, and a ball-bearing 25 interposed between the removable means and the top of the spindle.

2. In a device of the character described, a fixed spindle, a whirl and a whirl-tube surrounding the same, a ball-bearing supported 30 at the top of the spindle, a cap-piece adjustable in the top of the whirl-tube toward or away from said ball-bearing, and a ferrule arranged to lock the cap-piece to said whirl.

3. In a device of the character described, a 35 fixed spindle, a whirl and a whirl-tube surrounding the same, a ball-bearing arranged

at the top of said spindle, a cap-piece adjustable in the top of the whirl-tube and constituting one of the members of the ball-bearing, a sleeve surrounding the upper end of 40 the whirl-tube, and springs having their ends engaging respectively the sleeve and the whirl-tube and adapted to hold a bobbin on the whirl-tube and whirl without lateral or vertical movement of the bobbin thereon. 45

4. In a device of the character described, a fixed spindle, a whirl and a whirl-tube surrounding the same, a perforated cap-piece in the whirl-tube, an upper ball-bearing engaging the cap-piece and supporting the whirl-tube upon the top of the spindle, a lower ball-bearing supporting the whirl at the base of the spindle, an oil cup or reservoir surrounding the spindle and ducts arranged in the 50 spindle for lubricating the ball-bearing of the 55 whirl.

5. In a device of the character described, a fixed spindle having a groove in its upper end, a ball supported in said groove, a whirl and a whirl-tube surrounding said spindle, a cap-piece adjustable in the top of said whirl-tube and grooved to receive the ball of the spindle, and said cap-piece bearing upon said ball to support and center the whirl upon said spindle. 60

In testimony whereof I have hereunto set 65 my signature in the presence of two subscribing witnesses.

MORRIS SUBBER.
